CLAIM

We claim the ornamental design for a cover for operator cab interior for construction machine with console box, as shown.

DESCRIPTION

FIG. 1 is a front, top and left side perspective view of a cover for operator cab interior for construction machine with console box showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
